UNITED STATES PATENT OFFICE.

FRANK G. JOHNSON, OF BROOKLYN, NEW YORK.

POCKET CIGAR-CLIPPER.

SPECIFICATION forming part of Letters Patent No. 274,201, dated March 20, 1883.

Application filed July 20, 1882. (No model.)

To all whom it may concern:

Be it known that I, FRANK G. JOHNSON, a citizen of the United States, residing in the city of Brooklyn, in the county of Kings and State of New York, have invented a new and useful Improvement in Pocket Cigar-Clippers, of which the following is a specification.

Figure 1 is a longitudinal vertical section through the line $\alpha\alpha$ of Fig. 4, with a cigar inserted to be clipped; Fig. 2, a similar view, with the cigar clipped; Fig. 3, a transverse vertical section through the line $z\alpha$ of Fig. 1; Fig. 4, a top view of Fig. 1, and Fig. 5 a top view of Fig. 1, showing a modified shape of the knife.

Similar letters refer to similar parts throughout the several views.

D is a circular piece of metal having in and passing through it a conical hole into which is inserted the cigar to be clipped.

A is a shank extending back from the lower side of the holder D, to the end of which is attached the spring-knife B, by means of the rivet a , Fig. 2. This spring knife B consists of a flat piece of spring-steel about a half an inch wide at its widest part, and of such thickness as to afford an elasticity that will yield to the action of the thumb and finger. The front end of this spring B, as shown at C, is bent down at about a right angle to the top part of it and brought to a cutting-edge and the line of the edge made V shape, as shown at C in Fig. 3. The back face of the conical holder D, vertically, is slightly curved to correspond with the slightly-curvilinear motion of the cutting-edge of the knife C. (Shown best in Fig. 1.)

Fig. 5 illustrates the knife end of the spring

B as being V shape in the horizontal direction, which leaves the cut on the cigar in the shape of the V. In giving the knife this shape it is necessary to have a corresponding portion in a V shape cut vertically out of the back part of the conical holder D, as also shown in Fig. 5.

The operation of the device is as follows: With one hand crowd the pointed end of the cigar into the conical hole of the holder D, and then, with the other hand, by means of the thumb and finger, as shown in Fig. 2, crowd the knife C down until the corners of the knife strike on the shank A, which cuts off the point of the cigar.

I am aware that pocket cigar-clippers have been made with plain-edged knives and with V-shaped knives, and with conical holders, with the knives hinged by means of a rivet at the back end of a shank attached to the conical holder, which require to be opened before the cigar is inserted. I am also aware that a double reversely-curved spring, with cutting ends, has been employed. Therefore I do not claim, broadly, a pocket cigar-clipper consisting of a conical holder and a hinged knife or a double reversely-curved spring with cutting ends; but

What I do claim, and desire to secure by Letters Patent, is—

A pocket cigar-clipper, constructed as described, consisting of the bent spring-knife B, conical holder D, and the intermediate rigid shank, A, combined in the manner and for the purposes set forth.

FRANK G. JOHNSON.
